(57) **CLAIM**

The ornamental design for a crystal resonator for bio-sensor,
as shown and described.

DESCRIPTION

FIG. 1 is a front view of a crystal resonator for bio-sensor of
a new design;

FIG. 2 is a back view thereof;

FIG. 3 is a left side view thereof;

FIG. 4 is a right side view thereof;

FIG. 5 is a plan view thereof;

FIG. 6 is a bottom view thereof; and,

FIG. 7 is an assembling view showing a condition wherein the
crystal resonator is incorporated in a sensing apparatus.

The broken line showing of structural features are included
for the purpose of illustrating non-claimed subject matter and
forms no part of the claimed design.
